(57) CLAIM

An ornamental design for a combined cigarette pack and lighter holder, as shown and described herein.

DESCRIPTION

FIG. 1 is a perspective view of the combined cigarette pack and lighter holder, showing my new design.

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

The broken lines in the drawings depict portions of the combined cigarette pack and lighter holder that form no part of the claimed design.
